UNITED STATES PATENT OFFICE.

FRANK McLAUGHLIN, OF PHILADELPHIA, PENNSYLVANIA.

DEVICE FOR DISPENSING FLUID OR PLASTIC MATERIAL.

1,235,351.

Specification of Letters Patent. Patented July 31, 1917.

Application filed July 29, 1916. Serial No. 112,000.

To all whom it may concern:

Be it known that I, FRANK McLAUGHLIN, a citizen of the United States, residing in Philadelphia, Pennsylvania, have invented 5 certain Improvements in Devices for Dispensing Fluid or Plastic Material, of which the following is a specification.

My invention consists of a dispensing device especially designed for use with plastic 10 or fluid material, the object of my invention being to effect discharge of a given quantity of the material whenever such discharge is desired and to prevent discharge of material at all other times. A special feature of my 15 invention is a shaving brush having this object in view.

In the accompanying drawing—

Figure 1 is a longitudinal section of a dispensing device constructed in accordance 20 with my invention;

Fig. 2 is a perspective view of certain elements of the device detached from one another;

Fig. 3 is a vertical sectional view illustrating a modification of my invention, and

Fig. 4 is a view similar to Fig. 1, but illustrating another modification of my invention.

A device constructed in accordance with 30 my invention may be used for dispensing plastic soap, grease, lubricant, or other material susceptible of flowing under pressure. For the purpose of illustrating my invention I have selected a shaving brush, and in 35 Fig. 1 the brush material is shown as carried by a head 1, threaded or otherwise removably mounted upon the handle member 2, in order that it can, after use, be removed from the handle for sterilizing purposes and 40 readily replaced by a sterilized brush member to which fresh soap is supplied from the handle.

The handle member is in the form of a tube open at the upper end and having at 45 the lower end a nozzle 3 which projects into the mass of bristles carried by the brush member 1, this nozzle having, at its lower end, a valve seat normally closed by a valve 4, as shown in Fig. 1, so as to prevent the 50 delivery of the soap to the mass of bristles except at such times as the valve 4 may be lifted from its seat.

The plastic soap is, by preference, contained in a cartridge 2^a fitting snugly to the 55 interior of the tubular handle 2 and open at both ends which, prior to the introduction

of the cartridge into the handle, are closed by readily removable caps. Snugly fitting to the inner wall of the cartridge is a plunger 5 having a central internally threaded nut which engages a screw stem 7 centrally located in the handle and secured at its upper end, in any desirable manner, to a revoluble ring 8, the latter being located beyond the removable cap 9 which normally closes the upper end of the tubular handle 2. The ring 8 has a bottom closure 10 in which are formed diametrically opposite openings 11 through which project downwardly extending fingers 12 located at 70 the opposite sides of a disk 13, which is thereby caused to rotate with the ring 8.

The fingers 12 also project downwardly through diametrically opposite openings 14 in the fixed cap 9 and those portions of the fingers which enter the openings 14 have one edge cam-shaped and the opposite edge straight, as shown in Fig. 2.

Located above and bearing centrally upon the disk 13 is a spring 15 which consists 80 preferably of a hub with radially projecting arms, the latter bearing upon a plate 16 which closes the top of the hollow ring 8, as shown in Fig. 1.

The screw stem 7 is tubular and the valve 85 4 has a stem 17 which projects upwardly through said screw stem and is secured to the disk 13 so as to partake of any vertical movement imparted to the latter.

Owing to the fact that the inwardly projecting fingers 12 of the disk 13 are abrupt on one face and inclined on the opposite face, said fingers have both a cam and a ratchet action, that is to say, they permit turning of the ring 8 in a direction which carries the inclined faces of the fingers into engagement with the adjoining edges of the openings 14 in the cap 9, the fingers then rising over said edges and traveling forwardly in contact with the back of the cap. Turning of the 95 ring 8 in the opposite direction is, however, when the fingers 12 occupy the openings 14, prevented by contact of the abrupt faces of said fingers with the rear edges of said openings 14. By reason of this construction the 100 screw stem 7 can only be turned in such direction as to cause downward feeding of the plunger 5.

Supposing that the parts are in the position shown in Fig. 1, with the valve 4 closed 110 against its seat at the end of the nozzle 3, turning of the ring 8 so as to bring the in-

clined faces of the fingers 12 into contact with the forward edges of the openings 14 in the cap 9 will cause lifting of the disk 13, valve stem 17 and valve 4 and compression of the spring 15 until the fingers 12 are free from the openings 14 and bear upon the back of the cap 9. Such bearing will continue for a half turn of the ring 8 or until the fingers 12 again register with the openings 14, whereupon the recoil of the spring 15 will cause the fingers to again enter the openings 14 prior to a repetition of the operation on the next half turn of the ring 8.

During the entire half turn of the ring 15 and of the screw stem 7 the plunger 5 will be fed forwardly and thus cause a given amount of the plastic soap to be delivered from the forward end of the nozzle 3 into the brush, but, as soon as the half turn has been completed, the valve 4 will again move forwardly onto its seat and thereby arrest any further delivery of soap from the nozzle. This cutting off of the flow is a positive cut off and hence preferable to one in which cessation of flow simply depends upon cessation of the forward movement of the plunger 5, because, owing to the fact that the soap is a plastic body and is always under more or less pressure, such flow might, in the absence 30 of a positive cut off, continue for some time after the cessation of the forward movement of the plunger.

When the cartridge 2^a has been emptied of its contents the cap 9 may be removed, carrying with it the ring 8, screw stem 7, valve stem 17 and the parts connected to or co-operating therewith. The empty cartridge shell may then be removed and a full cartridge inserted in the tube 2 in place of the same and, after screwing back the plunger 5 to the top of the screw stem 7, the parts may be restored to their operative positions by reapplying the cap 9. In order to maintain the ring 8 in its proper vertical position in respect to the cap 9 the screw stem 7 has, at the top, a flange or shoulder bearing against the under side of said cap, as shown in Fig. 1.

If it is desired to lessen the amount of soap delivered to the brush on each operation of the ring 8 the number of equidistantly spaced fingers 12 and openings 14 may be increased, or if a longer flow is desired the number of such fingers and openings may be diminished.

In Fig. 3 for instance I have shown a construction in which the cap 9 has but one opening 14^a and there is but one finger 12^a for co-operation therewith.

In the latter case I prefer to substitute for the disk 13 a lever 20 fulcrumed at one end at one side of the ring 8 and having, at the opposite end, a depending finger 12^a, said lever bearing, at a point between the fulcrum 65 and the finger, upon a collar 13^a, or other

equivalent device on the valve stem 17, which collar takes the place of the disk 13 shown in Fig. 1.

In each of the devices thus far described the conjoint and co-operative action of the plunger 5 and valve 4 is effected by the partial rotation of the ring 8.

In the construction shown in Fig. 4, the cartridge 2^a is provided at its rear end with a cap 27 in which is revolvably mounted the rear end of the hollow screw stem 7, the latter projecting through the cap and having a notched flange 28, which is engaged by fingers 29 projecting forwardly from the hub of the ring 8 so as to insure the rotation 80 of the screw stem 7 with said ring 8.

In this case each cartridge is provided with its own screw stem and plunger which are discarded with the empty cartridge.

The cartridge has formed in one side a depression 30 engaged by an internally projecting lug 31 on the handle member so as to prevent turning of the cartridge with the screw stem 7.

If the cartridge has the nozzle 3 formed upon its forward end, the handle member 2 may consist of a simple tube with permanent closure at the rear end and open at the front end.

I claim:

1. In a device for dispensing plastic or fluid material, the combination of a tubular container for said material, said container having a discharge opening at its forward end, a plunger for imparting pressure to said material, means for moving said plunger forwardly, a valve seated in said discharge opening of the container, a longitudinally movable valve stem, and means for simultaneously imparting forward movement to the plunger and rearward movement to said valve stem.

2. In a device for dispensing plastic or fluid material, the combination of a tubular container for said material, said container having a discharge opening at its forward end, a plunger for imparting pressure to said material, said plunger having a central threaded opening, a hollow screw stem engaging said threaded opening of the plunger, a valve seated in said discharge opening of the container, a valve stem passing through said hollow screw stem, means for rotating said screw stem, and cam mechanism whereby as the screw stem is turned forwardly 110 the valve stem will be alternately raised and lowered.

3. In a device for dispensing plastic or fluid material, the combination of a container for said material, a valve for controlling the discharge of material from said container, a plunger for imparting pressure to said material, a tubular screw stem in threaded engagement with said plunger, a rotatable ring connected to said screw stem, 125

- a valve rod separate from said screw stem, but extending through the same, and a lifting device for said rod also carried by said ring.
- 5 4. In a device for dispensing plastic or fluid material, the combination of a container for said material, a valve for controlling the discharge of material from said container, a plunger for imparting pressure to said material, a tubular screw stem in threaded engagement with said plunger, a rotatable ring connected to said screw stem, a valve rod separate from said screw stem, but extending through the same, and an operating device for said rod in engagement with said ring, said operating device comprising a member in engagement with the valve rod, cam mechanism rotating with the ring and serving during continuous forward 10 rotation of the ring to first raise and then release the valve rod member, and resilient means acting on said valve rod member to lower the same when it is released from the action of the cam mechanism.
- 15 5. In a device for dispensing plastic or fluid material, the combination of a container for said material, a valve for controlling the discharge of material from said container, a plunger for imparting pressure to said material, a tubular screw stem in threaded engagement with said plunger, a rotatable ring connected to said screw stem, a valve rod separate from said screw stem, but extending through the same and a lifting 20 device for said rod operatively connected to said ring, said lifting device comprising a member in engagement with the valve rod, a finger projecting from said member, said finger having one inclined face and one abrupt face, and a fixed member for engagement with said fingers, said fixed member serving during continued forward movement of the ring to first lift and then release the valve rod and then prevent backward turning of the ring.
- 25 In testimony whereof, I have signed my name to this specification, in the presence of two subscribing witnesses.
